(57) **CLAIM**

The ornamental design for a spherical colander, as shown and described.

DESCRIPTION

FIG. 1 is a side isometric view of a spherical colander showing my new design.

FIG. 2 is a side isometric view thereof.

FIG. 3 is a top isometric view thereof.

FIG. 4 is a bottom isometric view thereof.

FIG. 5 is an isometric view of the bottom portion, separated for clarity of illustration.

FIG. 6 is a front view of FIG. 5.

FIG. 7 is a side view of FIG. 5.

FIG. 8 is a top isometric view of FIG. 5.

FIG. 9 is an isometric view of the top portion, separated for clarity of illustration.

FIG. 10 is a side view of FIG. 9.

FIG. 11 is a front view of FIG. 9.

FIG. 12 is a top isometric view of FIG. 9.

FIG. 13 is a bottom isometric view of FIG. 9; and, FIG. 14 is a bottom isometric view of FIG. 5.
